JOSEPH L. BUCKLEY, OF TRENTON, NEW JERSEY, ASSIGNOR, BY MESNE ASSIGNMENTS, TO PROCTOR & SCHWARTZ, INCORPORATED, OF PHILADELPHIA, PENNSYLVANIA, A CORPORATION OF PENNSYLVANIA.

DRYING APPARATUS.

Application filed March 19, 1920. Serial No. 367,108.

To all whom it may concern:

Be it known that I, JOSEPH L. BUCKLEY, a citizen of the United States, and resident of Trenton, in the county of Mercer and State of New Jersey, have invented a new and useful Improvement in Drying Apparatus, of which the following is a specification.

This invention relates to an improvement in apparatus for drying or conditioning articles composed of clay, porcelain or the like, with the object in view of providing such an apparatus which occupies a minimum of floor space while being capable of rapidly and simultaneously drying a large number of articles.

Another object is to provide such an apparatus, in which the articles to be dried may be progressively subjected to appropriate conditions of treatment and in appropriate positions, in order to produce a uniform product.

Another object consists in providing certain improvements, in the form, construction and arrangement of the several parts, whereby the above named and other objects may be effectively attained.

A practical embodiment of the invention is represented in the accompanying drawings, in which—

Fig. 1 represents a longitudinal vertical section through the apparatus.

Fig. 2 represents an end elevation of the same.

Fig. 3 represents a detail elevation, partly broken away, on an enlarged scale, showing the tray with articles to be dried thereon. Proportions are not maintained in this view, in order to better illustrate the construction.

The apparatus includes a rectangular enclosure or housing 1, which is preferably composed of angle iron framework and thermo-insulated plates removably secured to the framework.

This construction is conventionally shown in the drawings but is fully described in my co-pending application, Serial No. 353,226, filed January 22nd, 1920. This construction is, generally considered, of standard form but, as set forth in said co-pending application, I prefer to make use of certain special features such as compos-

ing the inner surface of the plates which constitute the walls, of galvanized steel, in order to prevent rust, and soldering all openings into the interior of the plates which may be made during the fitting of the parts, in order to prevent access of moisture to the insulating material.

The enclosure 1 is divided into several different compartments by means of transverse partitions which extend from side to side thereof. One of these partitions is denoted by 2 and is vertically disposed near the right hand end of the enclosure (as seen in Fig. 1). This partition is spaced from the top and bottom of the enclosure and is connected to a horizontally disposed partition 3, which extends first upwardly at an acute angle to the partition 2 and then at right angles to the partition 2. This partition 3 projects toward the left in Fig. 1. Another vertical partition is denoted by 4 and lies parallel to the partition 2. The partition 4 abuts the partition 3 and is spaced from the bottom and top of the enclosure. Another partition is marked 5 and is located vertically at the end of the enclosure opposite the partition 2. Partition 5 is also spaced from the bottom and top of the enclosure 1 and it has substantially the same extent as partition 2, though it is somewhat nearer the adjacent end of the enclosure than is the latter. Another partition 6 is horizontally disposed in spaced relation to the bottom of the enclosure. One end is bent, as indicated at 7, and formed integral with or connected to the lower extremity of the partition 4. The other end of the partition 6 is spaced a short distance from the lower end of partition 5. These partitions are somewhat diagrammatically illustrated and it will be understood that they are appropriately secured to and supported by the angle iron framing of the housing.

As a result of this arrangement of partitions, the enclosure is divided into what may be considered as four compartments vertically arranged. One of these compartments may be called the drying compartment and its scope is designated by the bracket 8. Another may be called the heating compartment and is designated by the bracket 9. The third may be called the auxiliary

compartment and is designated by the bracket 10. The fourth may be called the auxiliary channel and is designated by the bracket 11. Means is provided for generating an air current within the enclosure, and this means consists of a fan 12 that is mounted on a shaft 13 which is journaled in a bearing 14, that is fitted in the partition 2. A beveled gear 15 is fixed to the end of the shaft 13 and meshes with another beveled gear 16 that is fixed on a shaft 17, which has its inner end mounted in a bearing 18 secured to the partition 2, and extends outwardly to the exterior of the housing 1. Its outer end is journaled in a bearing 19 fixed in the wall of the housing and carries a pulley 20 which is designed to be driven from any suitable source of power, not shown.

20 The fan 12 is disposed in an opening formed in the partition 4 and bounded by a flange 21 and the partition 3. These last named parts serve as a shield around the periphery of the fan and compel the air current generated thereby to proceed substantially exclusively in an axial direction from the fan.

25 A large perforated baffle plate 22, which may be referred to as of grated form, is vertically disposed and extends transversely from side to side of the enclosure 1 in parallelism with and toward the inner part of the enclosure from the partition 5. This baffle plate 22 abuts the top of the enclosure 35 and is spaced from and directly above the end of the partition 6 which is adjacent the partition 5; the distance between the partitions 5 and 6 being substantially the same as the distance between the partition 6 and the baffle plate 22. The baffle plate 22 is spaced from the partition 5 about the same distance that the said partition is spaced from the adjacent wall of the enclosure. The part of the baffle plate 22 40 which projects above the partition 5 is solid, for a reason to be hereinafter set forth. The arrangement of these parts is such as to subdivide the drying compartment 8 into three sections. One of these may be 45 called the main or diffusing chamber 23, since the air current is diffused therein. Another may be called the duct 24, which is bounded by the baffle plate 22 and partition 5; while the third may be called the horizontal branch 25, which is bounded by the partition 6 and the bottom of the enclosure.

50 As a result of the arrangement just described, it will be seen that the air current generated by the fan 12 passes longitudinally through the enclosure 1, moving to the left in Fig. 1, until it encounters the baffle plate 22. This baffle plate will impede and break up the air current, but a considerable amount will pass through the baffle into the duct 24 and impinge against the parti-

tion 5, after which it will take a downward course passing through the opening between the partitions 5 and 6, then along below the partition 6 through the branch 25 and finally be drawn by the fan up between the partitions 6 and 4 on the one hand and the partition 2 on the other, and again sucked into the fan to be propelled a second time on its course. The bent portion 7 of the partition 6 facilitates the return of the air 70 to the fan since it provides a sort of funnel shape at this point. The action just described accounts for the major portion of the air current, but it may be mentioned that a certain amount will proceed directly 75 from the fan to and between the baffle 22 and partition 6, then between the partitions 5 and 6 and so on back to the fan. The solid upper portion of the baffle 22 prevents the air from passing over the partition 5 and 80 out of the feed opening in the enclosure, to be hereinafter mentioned; while the fact that the partition 5 is solid, prevents the air which passes through the perforated or grated part of the baffle 22 from passing 85 out the said feed opening. Hence, the air current is conserved within the enclosure and required to take an open circular course 90 through the drying and heating compartments, 8, 9. 95

I also provide within the enclosure means for heating the air current and this means preferably consists of a large radiator 26 and a pair of small radiators 27, 28. The large radiator 26 is located immediately in front of the fan 12 and extends substantially from the partition 3 to the partition 6. The smaller radiators are located, one about the middle of the diffusing chamber 23 and the other somewhat nearer to the baffle plate 22. These radiators are preferably composed of cast iron in order to eliminate rusting and may extend transversely from side to side of the enclosure and be supported on suitable angle iron framing. I prefer to equip each radiator with its own controlling means so as to be able to regulate the supply of steam to each independently of the others, for the purpose of varying the temperature in different parts of the enclosure when desired, and, as they are well understood by those acquainted with this art, no illustration or description is necessary. I also prefer to attach steam traps to the discharge end of each radiator 100 so that the water of condensation may pass out of the coil while the trap retains the pressure within the radiator, thereby securing the maximum heat output with a minimum number of radiators, and thus also 105 effecting an economy. 110

115 Means is provided for transporting the articles to be dried through the enclosure in contact with the heated air current, and this means consists of a pair of endless 120

sprocket chains 29, 30, which are mounted adjacent each side of the enclosure 1 and pass around sets of sprockets. One set of these sprockets is diagrammatically represented in Fig. 1 and includes the sprockets 31, 32, 33, 34, 35, 36, 37 and 38. It will be understood that the other set of sprockets is exactly like that just described and is similarly mounted at the opposite side of the enclosure. Each pair of sprockets is fixed to a shaft which is mounted in the framework of the sides of the enclosure and extends transversely through the enclosure. These shafts are denoted by 39, 40, 41, 42, 15 43, 44, 45 and 46.

In order to provide means for actuating the chains 29, 30, so as to cause them to travel on their endless course, the shaft 44 is driven through a worm wheel 47 which is 20 fixed thereto. This worm wheel is engaged by a worm 48 which is carried on a shaft 49 that has a worm wheel 50 that is fixed to a shaft 52 journaled in bearings 53, 54, on the top of the enclosure. The shaft 49 25 has its lower end mounted in a bearing 55 secured to the side of the enclosure and its upper end mounted in the bearing 54. A stepped pulley 56 is secured to the end of the shaft 52 in order to receive a belt drive 30 from a source of power not shown. It will be noted that the drive for the chains 29, 30, is separate from the drive for the fan 12, so that the latter may be continued in operation even though the chains are motionless.

As an immediate means of supporting the articles to be dried, I provide trays, each of 40 which consists of end members 57 and a shelf member 58. The end members 57 are pivoted to pins 59 that are secured to the chains 29, 30, so that the trays are suspended in a swinging manner from the said chains and will thus be carried throughout the endless course of the chains when the latter 45 are driven. The shelf members 58 are preferably composed of wood and provided with a series of vertical pins 60, which are preferably composed of copper. These pins provide means for supporting the articles to be dried, such as plates 61, on their edges 50 so as to enable the heated air current to thoroughly contact with all surfaces of the said plates.

The housing is provided with a loading 55 opening or door 62 and a discharge opening 63; although, in some cases, it may be desirable to both load and unload through the opening 62.

In operation, heat will be supplied to the 60 radiators 26, 27, 28 and the fan 12 and chains 29, 30 set in operation. The articles to be dried are now placed upon the shelves 58 of the trays as the latter slowly pass the feed opening 62. As the articles pass up 65 between the partition 5 and the adjacent end

of the housing it will be noted that they are out of contact with the heated air current, being shielded by the partition 5. Nevertheless, they are subjected to a certain elevated temperature which serves to initiate 70 the drying operation. After the articles have passed the sprocket 31 and start their downward course through the duct 24, they begin to be impinged upon by the heated air current shifting through the perforations in 75 the baffle 22. The air which passes through this baffle will be broken up so that its full force will not be exerted against the articles to be dried and furthermore it will, as a result of passing through the perforations 80 in the baffle 22, pass into the duct 24 in various angular directions so as to contact thoroughly with all parts of the articles. It will be noted that this contact of air on the articles in the duct 24 will at first be 85 in a direction substantially at right angles to the path of movement of the articles and then, as the current is deflected downwardly by the partition 5, the contact will be in a direction parallel to the movement of the 90 articles. After the articles pass the sprocket 32 and start their upward course toward the sprocket 33, they will come in direct contact with the heated air current moving at right angles to their travel and will also 95 come under the influence of the radiator 28. The travel of the articles from the sprocket 33 to the sprocket 34, will be under conditions of still greater heat and force of air current, as they will then be passing between the radiators 28 and 27 and also be 100 nearer the fan 12. After the articles have passed the sprocket 34 and move toward the sprocket 35, they will be subjected to the hottest of the air blast for the purpose of 105 finishing the drying operation. Upon rounding the sprocket 35, the articles will move along in the upper part of the enclosure past the sprocket 36 and down in the auxiliary compartment 10 until they reach 110 the opening 63, at which time they may be unloaded from the trays. Under certain circumstances, if desired, the articles may be permitted to pass the opening 63 and continue on through the branch 25 until they 115 reach the opening 62 where they may be unloaded.

From the foregoing, it will be seen that the articles are subjected to a progressive 120 drying operation in which the effect of the heat and air is increased as the articles move through the enclosure; and that the heated air current is maintained within the enclosure, travelling in an endless course 125 throughout the operation. The arrangement of all parts is such as to provide a thorough and intimate contact of the drying air with the articles; and it may be mentioned that the blowing of the air through the radiators not only heats it, but also 130

serves to somewhat dissipate or diffuse it and thus increase its effect.

It will be understood that various changes may be resorted to in the form, construction and arrangement of the several parts without departing from the spirit and scope of my invention; and hence I do not intend to be limited to the details herein shown and described, except as they are included in the claims.

What I claim is:

1. Apparatus of the character described comprising, an enclosure, carrier means for transporting articles to be dried through said enclosure in a course including substantially vertical elements, a fan located at one side of a majority of the said elements for generating an air current in a substantially horizontal direction, heating means between the fan and the said majority of elements, and heating means between other elements.

2. Apparatus of the character described comprising, an enclosure including a drying compartment, said compartment being encompassed at its ends by solid transverse partitions, whereby auxiliary channels are formed between each end of the said drying compartment and the walls of the enclosure which channels are substantially free from the drying medium.

3. Apparatus of the character described comprising, an enclosure including a drying compartment, said compartment being encompassed at its ends by solid transverse partitions, whereby auxiliary channels are formed between each end of the said drying compartment and the walls of the enclosure which channels are substantially free from the drying medium, the wall of the enclosure having a loading aperture opening into one of said channels.

4. Apparatus of the character described comprising, an enclosure including a drying compartment, said compartment being encompassed at its ends by solid transverse partitions, whereby auxiliary channels are formed between each end of the said drying compartment and the walls of the enclosure which channels are substantially free from the drying medium, the walls of said enclosure having loading and unloading apertures opening into said channels.

5. Apparatus of the character described comprising, an enclosure including a drying compartment, said compartment being encompassed at its ends by solid transverse partitions, whereby auxiliary channels are formed between each end of the said drying compartment and the walls of the enclosure which channels are substantially free from the drying medium, and carrier means traversing the drying compartment and the channels.

6. Apparatus of the character described

comprising, an enclosure including a drying compartment, said compartment being encompassed at its ends by solid transverse partitions, whereby auxiliary channels are formed between each end of the said drying compartment and the walls of the enclosure which channels are substantially free from the drying medium, the wall of the enclosure having a loading aperture opening into one of said channels, and carrier means traversing the drying compartment and the channels.

7. Apparatus of the character described comprising, an enclosure including a drying compartment, said compartment being encompassed at its ends by solid transverse partitions, whereby auxiliary channels are formed between each end of the said drying compartment and the walls of the enclosure which channels are substantially free from the drying medium, the walls of said enclosure having loading and unloading apertures opening into said channels, and carrier means traversing the drying compartment and the channels.

8. Apparatus of the character described comprising, an enclosure including a drying compartment, said compartment being encompassed at its ends by solid transverse partitions, said partitions being spaced from the top and bottom of the enclosure, means between said partitions for generating an air current moving longitudinally of said compartment, and a baffle for interrupting the course of said current and preventing it from passing over one of said partitions and out of the drying compartment.

9. Apparatus of the character described comprising, an enclosure including a drying compartment, said compartment being encompassed at its ends by solid transverse partitions, said partitions being spaced from the top and bottom of the enclosure, means between said partitions for generating an air current moving longitudinally of said compartment, a baffle for interrupting the course of said current and preventing it from passing over one of said partitions and out of the drying compartment, the bottom of the drying compartment having an opening therein.

10. Apparatus of the character described comprising, an enclosure including a drying compartment, said compartment being encompassed at its ends by solid transverse partitions, said partitions being spaced from the top and bottom of the enclosure, means between said partitions for generating an air current moving longitudinally of said compartment, and a baffle for interrupting the course of said current and preventing it from passing over one of said partitions and out of the drying compartment, said baffle being connected to the top.

of the enclosure and being perforated below the level of the top of the adjacent partition.

11. Apparatus of the character described comprising, an enclosure including a drying compartment, said compartment being encompassed at its ends by solid transverse partitions, said partitions being spaced from the top and bottom of the enclosure, 5 means between said partitions for generating an air current moving longitudinally of said compartment, a baffle for interrupt-

ing the course of said current and preventing it from passing over one of said partitions and out of the drying compartment, 15 the bottom of the drying compartment having an opening therein, said baffle being connected to the top of the enclosure and being perforated below the level of the top of the adjacent partition. 20

In testimony, that I claim the foregoing as my invention, I have signed my name this seventeenth day of March, A. D. 1920.

JOSEPH L. BUCKLEY.
